EVERETT STUCK, OF SYRACUSE, NEW YORK, ASSIGNOR TO OLIVER M. EDWARDS, OF SYRACUSE, NEW YORK.

FOLLOWER MECHANISM FOR FILING-CABINETS.

1,116,757.

Specification of Letters Patent. Patented Nov. 10, 1914.

Application filed May 29, 1913. Serial No. 770,611.

To all whom it may concern:

Be it known that I, EVERETT STUCK, of Syracuse, in the county of Onondaga and State of New York, have invented a certain new and useful Follower Mechanism for Filing-Cabinets, of which the following is a specification.

This invention has for its object the production of a follower mechanism for filing cabinets and the like which is simple in construction, economical for manufacture and highly efficient and durable in use and it consists in the combinations and constructions hereinafter set forth and claimed.

15 In describing this invention reference is had to the accompanying drawings in which like characters designate corresponding parts in all the views.

Figure 1 is a cross-sectional view of a draw, embodying my follower mechanism, the same being shown in rear elevation. Fig. 2 is a longitudinal vertical sectional view taken centrally of Fig. 1. Fig. 3 is a detail view of parts seen in Figs. 1 and 2.

25 This follower mechanism for filing cabinets comprises a guide, a slide movable in the guide and coacting at its side margins with the guide, and a clamping member carried by the follower and coacting with the 30 guide.

1 is the draw which is here shown as formed up out of sheet metal.

2 is the guide which, as here shown, is in the form of a channel extending lengthwise 35 of the bottom of the member 1 and as having its side margins 3 overhanging the bottom of the channel. This guide, as here shown, is located in a depression 4 formed in the bottom 5 of the draw, and is provided 40 with perforations in its bottom which receive ears 6 struck from bottom of the depression 4 and inserted through said perforations and bent over onto the bottom of the guide 2 to hold the guide in position.

45 7 is the slide movable along the guide and secured to the follower plate 8; and 9 is the clamping member pivoted to a bracket to be described on the follower plate 8 and coacting with the guide 2 and with the slide 7 to 50 hold the follower and associated parts in any position along the guide 2. The slide 7 is formed of sheet metal and has its side margins running under the overhanging margins 3 of the guide 2, these side margins

10 being bent into angular form to conform 55 to the angle formed by the overhanging margins 3 and the sides 11 of the guide 2, and these angular margins are preferably arranged with their edges running on the bottom of the channel of the guide 2. However, 60 if desired, the angular formation of the margins of the slide 7 may be modified or dispensed with. The slide 7 is usually formed with a central lengthwise depression 12 for receiving the card guide rod 13 and 65 the angular formation of the margins of the guide 2 provide ample room for this depression without forming a slot or depression in the bottom of the channel 2. The depression 12 terminates short of the bottom of the 70 channel 2 in order to clear the ears 6. The slide 7 is connected to the follower plate 8 by means associated therewith as a bracket secured to the lengthwise intermediate portion of the slide 7 between the overhanging 75 margins of the guide. To facilitate the securing of the bracket to the slide, the slide is raised between the overhanging margins 3 of the guide 2 and above said margins as illustrated at 14, and the depression 12 de- 80 pends centrally from the raised portion.

The bracket is here shown as U shaped having its intermediate portion secured to the raised portion 14 of the slide 7 and its branches extending upwardly; and this U 85 shaped bracket is preferably provided by forming horizontally and rearwardly extending flanges 15, 16 on the follower plate, the flange 15 being at the lower edge of the follower plate 8, said flange overlying the 90 portion 14 of the slide 7, and the vertically extending flanges 16 meeting the flange 15. The flanges 15, 16 are struck from the sheet metal follower plate, and the flange 15 is preferably formed with upturned ends 95 which are secured by rivets 17 or any other suitable fastening means to the vertical flanges 16. The flange 15 is secured to the intermediate portion 14 of the slide 7 by means of rivets 18 or any other suitable fastening means, these rivets also passing through a bearing plate 19 resting on the upper face of the flange 15.

The operating member 9 is pivoted to the vertical flanges 16, and is here shown as 105 provided with side flanges 20 arranged contiguous to the vertical flanges 16, the pivot 21 for the clamping member 9 ex-

tending through the flanges 16 of the follower and 20 of the clamping member 9. A suitable spring 22 is interposed between the follower and the clamping member 9 to hold the clamping member in its operative position. The lower end of the clamping member coacts with the upper faces of the overhanging margins 3 and said member is located in the rear of the follower and 5 coacts with the guide at a point slightly in the rear of the slide 7, and the slide 7 preferably extends in front of the follower plate from a point substantially flush with the rear edge of the horizontal edge 15. This 10 arrangement permits the slide 7 to bind against the guide 2 when force is applied to the front face of the follower plate, and the clamping member 9 has not been operated; but not to bind when pressure is applied to 15 the follower plate to force the same forwardly.

The follower mechanism is particularly simple and economical in construction owing to the arrangement of the parts by which 20 the slide, follower and clamping member are assembled, and to the arrangement by which provision for the card guide rod is made.

What I claim is:—

30 1. A follower mechanism for filing cabinets comprising a guide in the form of a channel having its side margins overhanging its bottom, and a slide movable in the guide and having its side margins running under the overhanging margins of the channel and bent into angular form to conform to the angles formed by the sides of the channel and the overhanging margins, substantially as and for the purpose described.

35 2. A follower mechanism for filing cabinets comprising a guide in the form of a channel having its side margins overhanging its bottom, and a slide movable in the guide and having its side margins running under the overhanging margins of the channel and bent into angular form to conform to the angles formed by the sides of the channel and the overhanging margins, the edges of 40 said margins of the slide running on the bottom of the channel, substantially as and for the purpose specified.

45 3. A follower mechanism for filing cabinets comprising a guide and a slide movable along the guide and engaging at its side edges with the guide, the slide being secured to the follower and being formed with a lengthwise depression for receiving a card retaining rod, substantially as and for the purpose set forth.

50 4. A follower mechanism for filing cabinets comprising a follower, a guide in the form of a channel having its side margins overhanging its bottom, and a slide movable in the guide and having its side margins running under the overhanging mar-

gins of the channel, the intermediate portion of the slide being secured to the follower and formed with a lengthwise depression for receiving a card retaining rod, substantially as and for the purpose described.

5. A follower mechanism for filing cabinets comprising a follower, a guide in the form of a channel having its side margins overhanging its bottom, and a slide movable in the guide and having its side margins running under the overhanging margins of the channel and bent into angular form to conform to the angles formed by the sides of the channel and the overhanging margins, and the intermediate portion of the slide being secured to the follower and formed with a lengthwise groove or depression for receiving a card retaining rod, substantially as and for the purpose specified.

6. A follower mechanism for filing cabinets comprising a follower, a guide in the form of a channel having its side margins overhanging its bottom, and a slide movable in the guide and having its side margins running under the overhanging margins of the channel, the portion of the slide between the margins thereof being raised above the overhanging margins of the guide and secured to the follower and formed with a central lengthwise depression for receiving the card guide rod, substantially as and for the purpose set forth.

7. A follower mechanism for filing cabinets comprising a follower plate, a guide, a slide movable along the guide and having its side margins engaging the guide, a bracket connecting the slide and follower plate, the bracket being mounted on the intermediate portion of the slide between its side margins, and a clamping member pivoted to the bracket, substantially as and for the purpose described.

8. A follower mechanism for filing cabinets comprising a follower plate, a guide in the form of a channel having its side margins overhanging its bottom, a slide movable in the guide and having its side margins running under the overhanging margins of the channel and intermediate lengthwise portions raised above the side margins thereof between the overhanging margins of the guide, a bracket connecting the slide and the follower plate, the bracket being mounted on the raised portion, and a movable clamping member pivoted to the bracket, substantially as and for the purpose specified.

9. A follower mechanism for filing cabinets comprising a follower plate, a guide, a slide movable along the guide and having its side margins engaging the guide, a U shaped bracket on the follower plate and having its intermediate portion mounted on the intermediate portion of the slide between the margins thereof and its branches

- extending upwardly and a movable clamping member pivoted to said branches, substantially as and for the purpose set forth.
10. A follower mechanism for filing cabinets comprising a follower plate, a guide in the form of a channel having its side margins overhanging its bottom, a slide movable in the guide and having its side margins running under the overhanging margins of the channel, a U shaped bracket on the follower plate and having its intermediate portion mounted on the intermediate portion of the slide and having its arms extending upwardly, and a clamping member pivoted to said arms, substantially as and for the purpose described.
11. A follower mechanism for filing cabinets comprising a follower plate, a guide, a slide movable along the guide and having its side margins engaging the guide, the follower plate being formed with a horizontally extending flange at its lower edge secured to the intermediate portion of the slide, and a clamping member pivotally connected above the flange to the follower plate and coacting with the upper faces of the said overhanging margins of the guide, substantially as and for the purpose specified.
12. A follower mechanism for filing cabinets comprising a follower plate, a guide in the form of a channel having its side margins overhanging its bottom, a slide movable in the guide and having its side margins running under the overhanging margins of the channel, the slide having its intermediate portion raised between the overhanging margins of the guide and the follower plate being formed with a horizontally extending flange at its lower edge overlying said raised intermediate portion of the slide and secured thereto; and a pivoted clamping member carried by the follower plate and coacting with the upper faces of the overhanging margins, substantially as and for the purpose set forth.
13. A follower mechanism for filing cabinets comprising a follower plate, a guide in the form of a channel having its side

margins overhanging the bottom, a slide movable in the guide having its side margins running under the overhanging margins of the channel, the follower plate being formed with means projecting therefrom and secured to the intermediate portion of the slide between said overhanging margins, and a clamping member pivoted to the said means and coacting with the upper faces of the overhanging margins, substantially as and for the purpose described.

14. A follower mechanism for filing cabinets comprising a follower plate, a guide, a slide movable along the guide and having its side margins engaging the guide, the follower plate being formed with a horizontally extending flange at its lower edge secured to the intermediate portion of the slide between its margins, the follower plate being also formed with vertically extending flanges meeting the ends of said horizontal flange, and a clamping member pivoted to the vertical flanges and coacting with the guide, substantially as and for the purpose specified.

15. A follower mechanism for filing cabinets comprising a follower plate, a guide, a slide movable along the guide and having its side margins engaging the guide, the follower plate being provided with a horizontally extending flange at its lower edge secured to the intermediate portion of the slide between the side margins thereof, said flange having upturned ends, the follower plate also having vertically extending flanges meeting the upturned ends and secured thereto, and a clamping member pivoted to the vertical flanges and coacting with the guide, substantially as and for the purpose set forth.

In testimony whereof, I have hereunto signed my name in the presence of two attesting witnesses, at Syracuse, in the county of Onondaga, in the State of New York, this 9th day of May, 1913.

EVERETT STUCK.
